COMBINATION IRON AND RUFFLER

Thomas W. Shaw, Chestnut Hill, Pa.

Application September 12, 1940, Serial No. 356,418

5 Claims. (Cl. 223—36)

The present invention has in view, as its foremost objective, the provision of a combination iron and ruffler.

The formation of ruffles in garments has always been a matter of considerable difficulty, both at the time of initial manufacture of the garment and subsequent to each laundering thereof. The present invention proposes to substantially reduce, if not entirely obviate, this difficulty by providing a flatiron with a ruffling plate the edge of which cooperates with the flatiron to form ruffles.

When a garment is being pressed, as is the custom after each washing thereof, the ordinary flatironing surface is needed, and there are only certain intervals when the functions of the ruffling plate are required. Accordingly a further object of the invention is the provision of a combination flatiron and ruffler in which the ruffling plate may be normally held in an out-of-the-way ineffective position that does not interfere with the normal use of the iron. However, provision is made to lower the ruffling plate into effective position as occasion demands.

The present invention is based on the discovery that ruffles may be nicely formed in garments by the cooperation of an ironing surface and an edge that projects slightly therebeneath at one side thereof. Accordingly, a further more detailed object of the invention is the provision of a combination iron and ruffler in which the edge of the ruffler plate is disposed at one side of the ironing surface.

Still more in detail the invention has, as an object, the provision of a combination iron and ruffler in which the ruffler plate is disposed at one side of the nose of the iron.

Particular objects and advantages of the invention are tied up with the manner in which the ruffler is mounted on the iron, and also with the provision of mechanism for causing the raising and lowering of the ruffler plate. These will in part become apparent, and in part be hereinafter stated, as the description of the invention proceeds.

The invention, therefore, comprises a combination iron and ruffler in which a ruffling plate is located at one side of the nose of the iron and is provided with mechanism for raising the same in an out-of-the-way ineffective position, and which mechanism may be operated to lower the ruffler plate into effective position in which the edge projects below the ironing surface.

For a full and more complete understanding of the invention reference may be had to the fol-

lowing description and accompanying drawing, wherein

Figure 1 is a view in side elevation of a combination iron and ruffler made in accordance with the precepts of this invention,

Figure 2 is a fragmentary view partly in section and partly in elevation, taken on a plane normal to the showing of Figure 1,

Figure 3 is an enlarged detailed perspective of the ruffler blade per se,

Figure 4 is a similar perspective of the guide structure on which the ruffler is mounted, and

Figure 5 is still another perspective of the operating member and associated cam.

In view of the present day widespread use of the electric iron the present invention is shown as incorporated in a conventional electric iron. It is to be understood, however, that this is intended to be no limitation on the invention.

Referring now to the drawing, wherein like reference characters denote corresponding parts, an electric iron is shown in Figure 1 and referred to in its entirety by the reference character E. The iron E is shown as including a sole 10 that provides an ironing surface at 11. Extending above the sole 10 is a casing 12 which houses the electrical heating elements. The iron E is shown as provided with the usual socket at 13 for plugging in with the source of current, and the conventional handle is shown at 14.

Referring for the moment more particularly to Figure 4, the guide structure for the ruffler attachment of this invention is shown as comprising a bracket member referred to in its entirety by the reference character B. This bracket B includes a base 15 formed with openings 16. Upstanding from the base 15, at one side thereof, is a guide bar 17 which terminates at the lower end in shoulders 18. Spaced from the guide bar 17 by blocks shown at 19 is an upstanding plate 20 that is substantially parallel to the guide bar 17. The members 17 and 20 are formed with aligned openings 21 and 22 through which a pivot member 23 is adapted to pass.

The opening 22 is threaded, as illustrated, and the headed end of the pivot pin 23 is also threaded, as shown at 24, these threads 24 being adapted to be screwed into the threaded opening 22.

Referring now more particularly to Figure 2, it will be noted that the sole 10 is cut away, as shown at 25, to provide a recess in which fits the base flange 15 of the bracket B. When this base flange 15 is so positioned, screw fastening elements shown at 26 pass through the openings 16 into threaded sockets within the sole 10 (dotted

lines, Figure 2) and thus securely anchor the bracket B in position. It will be noted that the casing 12 is cut away, as shown at 27, to accommodate the upstanding structure of the bracket B.

Referring now more particularly to Figure 3, the ruffer plate is designated P. This plate P is formed with a lower ruffling edge at 28 of a proper degree of sharpness, and it will be noted that the plate P is reduced in extent towards the top to provide a reduced upper extension 29. A pair of side spacing members 30 and 31 are secured to one face of the extension 29, and are spaced apart to define a channel 32. This channel 32 is closed by a substantially rectangularly shaped plate 33 that is cut away centrally to provide the central recess 34.

It is notable that the reduced extension 29, spaces 30 and 31 and plate 33 define a guideway which receives the guide bar 17. When the plate P is positioned with this guide bar 17 received in the channel 32 the plate 33 is disposed between members 17 and 20, as shown in Figure 2.

Referring now more particularly to Figure 5, an operating member is shown in the form of a handle element 35 that is provided at the bottom with an opening 36 through which the pivot pin 23 is adapted to pass. Immediately adjacent that portion of the handle 35 formed with the opening 36 is a cam member 37 that is formed with an opening in alignment with the opening 36. This cam member projects into the opening 34 of the plate 33, and the cam surfaces of the member 37 are designed to effectively engage the surfaces of the opening 34 to cause upward or downward movement of the plate P.

When the iron is to be used in the normal manner in which a flatiron is used the handle 35 assumes the dotted line position of Figure 1, in which event the plate P also assumes the dotted line position of Figure 1, and in which position the edge 28 is disposed above the ironing surface 11. Thus it is in an out-of-the-way ineffective position which in no way interferes with the conventional use of the iron.

However, when the operator is desirous of forming ruffles the handle 35 is raised into the full line position of Figure 1. As this operating member 35 swings about the pivot pin 23 the cam 37 is rotated, and the cam surfaces thereof engaging with the surfaces of the cut-out 34 of plate 33 move the plate P downwardly into the full line position of Figure 1. In this position it is notable the edge 28 of the ruffer plate P is disposed below the ironing surface 11.

The operator now grasps the handle 14 in his right hand, and with his left hand grasps loosely one edge of the garment in which the ruffles are to be formed. He now moves the iron in a side-wise direction away from the left hand while "guiding" the portion of the garment with the left hand. The ironing surface 11 first causes a pressing of the fabric, but the edge 28 bites into the fabric and pulls it thru the left hand to cause gatherings that form the ruffles in the fabric.

In the illustrated embodiment of the invention the combination iron and ruffer are shown as designed for use by a right-handed person; that is it is intended that the iron be grasped by the person's right hand, and the garment in which the ruffles are being formed by the user's left hand. However, it is obvious that the combination iron and ruffer could be designed for use by left-handed people by merely positioning the ruffer plate P on the other side of the nose of the iron.

While a preferred specific embodiment of the invention is hereinbefore set forth it is to be clearly understood that the invention is not to be limited to the exact constructions illustrated and described, because various modifications of these details may be provided in putting the invention into practice within the purview of the appended claims.

I claim:

- 10 1. In combination, an electric iron including a sole having an ironing surface, and a casing disposed above said sole, a bracket anchored to said sole and projecting through said casing, and a ruffer plate movably mounted on said bracket to elevate one portion of said ironing surface from its normal horizontal plane while leaving another portion of said ironing surface in said normal horizontal plane.
- 15 2. In combination, an electric iron including a sole having an ironing surface formed with a nose, a bracket anchored to said sole at one side of said nose, a ruffer plate slidably mounted on said bracket and conforming in shape to the shape of said nose, said ruffer plate being positioned at one side of said nose and in close contact therewith adjacent an edge of said ironing surface, said ruffer plate having an edge that is adapted to be disposed beneath said ironing surface, and means for moving said plate into and out of position in which said edge is below said ironing surface.
- 20 3. In combination, an electric iron including a sole having an ironing surface and formed with a nose, a bracket anchored to said sole at one side of said nose, a ruffer plate slidably mounted on said bracket and conforming in shape to the shape of said nose and in close contact therewith adjacent an edge of said ironing surface, said ruffer plate being positioned at one side of said nose, said ruffer plate having an edge that is adapted to be disposed beneath said ironing surface, cam means carried by said bracket and engaging said ruffer plate, and an operating member for causing rotation of said cam means to raise and lower said ruffer plate.
- 25 4. In combination, an iron having an ironing surface defined by two side edges, one of said side edges being unencumbered to permit of engagement of said edge with the work, and a ruffer plate carried at the other side edge and having an edge disposed beneath the plane of said ironing surface, said ironing surface being tilted with respect to the work when said unencumbered edge and said plate edge engage the work whereby a gathering receiving space is provided between said ironing surface, ruffer plate and the work.
- 30 5. In combination, an iron formed with a nose and having an ironing surface defined by two side edges which meet at said nose, one of said side edges being unencumbered to provide for its engagement with the work, and a ruffer plate carried at the other side edge and extending over a portion of said edge proximate to said nose, said ruffer plate having an edge disposed beneath the plane of said ironing surface and adapted to engage the work simultaneously with said engagement of the work by said edge of the ironing surface whereby said ironing surface is tilted with respect to the work and a gathering receiving space is provided between said ironing surface, ruffer plate, and the work.
- 35 6. In combination, an iron formed with a nose and having an ironing surface defined by two side edges which meet at said nose, one of said side edges being unencumbered to provide for its engagement with the work, and a ruffer plate carried at the other side edge and extending over a portion of said edge proximate to said nose, said ruffer plate having an edge disposed beneath the plane of said ironing surface and adapted to engage the work simultaneously with said engagement of the work by said edge of the ironing surface whereby said ironing surface is tilted with respect to the work and a gathering receiving space is provided between said ironing surface, ruffer plate, and the work.
- 40 7. In combination, an iron formed with a nose and having an ironing surface defined by two side edges which meet at said nose, one of said side edges being unencumbered to provide for its engagement with the work, and a ruffer plate carried at the other side edge and extending over a portion of said edge proximate to said nose, said ruffer plate having an edge disposed beneath the plane of said ironing surface and adapted to engage the work simultaneously with said engagement of the work by said edge of the ironing surface whereby said ironing surface is tilted with respect to the work and a gathering receiving space is provided between said ironing surface, ruffer plate, and the work.
- 45 8. In combination, an iron formed with a nose and having an ironing surface defined by two side edges which meet at said nose, one of said side edges being unencumbered to provide for its engagement with the work, and a ruffer plate carried at the other side edge and extending over a portion of said edge proximate to said nose, said ruffer plate having an edge disposed beneath the plane of said ironing surface and adapted to engage the work simultaneously with said engagement of the work by said edge of the ironing surface whereby said ironing surface is tilted with respect to the work and a gathering receiving space is provided between said ironing surface, ruffer plate, and the work.
- 50 9. In combination, an iron formed with a nose and having an ironing surface defined by two side edges which meet at said nose, one of said side edges being unencumbered to provide for its engagement with the work, and a ruffer plate carried at the other side edge and extending over a portion of said edge proximate to said nose, said ruffer plate having an edge disposed beneath the plane of said ironing surface and adapted to engage the work simultaneously with said engagement of the work by said edge of the ironing surface whereby said ironing surface is tilted with respect to the work and a gathering receiving space is provided between said ironing surface, ruffer plate, and the work.
- 55 10. In combination, an iron formed with a nose and having an ironing surface defined by two side edges which meet at said nose, one of said side edges being unencumbered to provide for its engagement with the work, and a ruffer plate carried at the other side edge and extending over a portion of said edge proximate to said nose, said ruffer plate having an edge disposed beneath the plane of said ironing surface and adapted to engage the work simultaneously with said engagement of the work by said edge of the ironing surface whereby said ironing surface is tilted with respect to the work and a gathering receiving space is provided between said ironing surface, ruffer plate, and the work.
- 60 11. In combination, an iron formed with a nose and having an ironing surface defined by two side edges which meet at said nose, one of said side edges being unencumbered to provide for its engagement with the work, and a ruffer plate carried at the other side edge and extending over a portion of said edge proximate to said nose, said ruffer plate having an edge disposed beneath the plane of said ironing surface and adapted to engage the work simultaneously with said engagement of the work by said edge of the ironing surface whereby said ironing surface is tilted with respect to the work and a gathering receiving space is provided between said ironing surface, ruffer plate, and the work.
- 65 12. In combination, an iron formed with a nose and having an ironing surface defined by two side edges which meet at said nose, one of said side edges being unencumbered to provide for its engagement with the work, and a ruffer plate carried at the other side edge and extending over a portion of said edge proximate to said nose, said ruffer plate having an edge disposed beneath the plane of said ironing surface and adapted to engage the work simultaneously with said engagement of the work by said edge of the ironing surface whereby said ironing surface is tilted with respect to the work and a gathering receiving space is provided between said ironing surface, ruffer plate, and the work.
- 70 13. In combination, an iron formed with a nose and having an ironing surface defined by two side edges which meet at said nose, one of said side edges being unencumbered to provide for its engagement with the work, and a ruffer plate carried at the other side edge and extending over a portion of said edge proximate to said nose, said ruffer plate having an edge disposed beneath the plane of said ironing surface and adapted to engage the work simultaneously with said engagement of the work by said edge of the ironing surface whereby said ironing surface is tilted with respect to the work and a gathering receiving space is provided between said ironing surface, ruffer plate, and the work.
